UNITED STATES PATENT OFFICE.

AMERICUS MIESSE, OF LIMA, OHIO, ASSIGNOR OF ONE-EIGHTH TO FRANK D. CARPENTER, ONE-EIGHTH TO FRED D. CLOSSER, ONE-EIGHTH TO FRANK W. DRAKE, ONE-EIGHTH TO WILLIAM H. HAY, ONE-EIGHTH TO RICHARD H. CARPENTER, AND ONE-EIGHTH TO HENRY M. REED, JOHN W. REED, AND JAMES F. REED, OF LIMA, OHIO.

HEADLIGHT.

No. 857,249.

Specification of Letters Patent.

Patented June 18, 1907.

Application filed June 16, 1906. Serial No. 322,074.

To all whom it may concern:

Be it known that I, AMERICUS MIESSE, a citizen of the United States, residing at Lima, in the county of Allen and State of Ohio, have invented a new and useful Improvement in Headlights, of which the following is a specification.

This invention relates to headlights and more particularly to adjustable screens for the same, the object being to provide a screen which can be readily attached to any of the ordinary headlights now in use, and one which can be operated easily and quickly from the cab of a locomotive, or the platform of a car, as the case may be.

Another object of my invention is to provide a screen which is mounted in a casing and adapted to work in the casing of the headlight, so that it will be protected from snow and rain at all times.

Another object of my invention is to provide a screen which can be adjusted to completely cut off the light, or a portion of it, as desired.

With these and various other objects in view, the invention consists in the novel features of construction, hereinafter fully described and pointed out in the claims.

In the drawings forming a part of this specification:—Figure 1 is a perspective view of a portion of a street-car showing my improved headlight in place. Fig. 2 is a longitudinal sectional view of the same. Fig. 3 is a section taken on lines 3—3 of Fig. 2. Fig. 4 is a perspective view of a portion of the headlight casing. Fig. 5 is a perspective view of the hollow frame. Fig. 6 is a perspective view of the screen casing. Fig. 7 is a perspective view of the screen. Fig. 8 is an enlarged detail sectional view. Fig. 9 is a detail longitudinal sectional view of a modification.

Referring to the drawings A indicates a cylindrical casing forming the body of my improved headlight which is provided with an ordinary cone-shaped reflector B, having openings B', formed therein, through which the chimney of an ordinary lamp is adapted to extend. A vent C is formed in the openings in the reflector, provided with a cap C'.

The casing is provided with a slot A', extending half-way around the top of the same, adjacent its forward end, over which the semi-circular portion of the hollow rectangular frame D, is adapted to be secured in any suitable manner. A cylindrical casing E, provided with a downwardly projecting hood E', is adapted to fit over the frame D, having a cap E', at one end to conform to the shape of the casing, and provided with an opening in which one end of the spring actuated roller F is secured, the other end of the roller being mounted in an opening in the end of the casing E. Secured to the bottom of the casing adjacent the front, are strips G, which are bent downwardly at G', then backwardly at G'', and then upwardly at G'', and slotted through which thumb-screws I² are adapted to pass into openings formed in the lower end of the strips I, secured to the back of the casing so that the lamp can be adjusted to set evenly on the platform J, of the car which is provided with a dash-board K, provided with a loop K² over which the hooked ends I' of the strips I, are adapted to fit and securely hold the headlight in place. Mounted on the roller F, is a screen L, of any suitable material having a curved lower end to conform to the shaft of the cylinder and to which a cord H is secured which passes over a pulley M, arranged in the bottom of the casing and out through a flexible tube N, arranged in the bottom of the casing which extends out through an opening in the end of the casing and opening in the dash-board, and is provided with a ring H', at its end adapted to fit over the hooks K', K'', secured on the dash-board K, so that the screen can be drawn over the headlight from the platform as desired. A door O is hinged to one side of the front end of the casing adapted to close the front of the casing provided with a glass O'.

In the modification shown in Fig. 9, I provide the door P with a slot over which the semi-circular portion of the hollow frame Q is adapted to fit, on which is secured the downwardly projecting hood of the casing R, in which a screen is adapted to be mounted.

Having thus fully described my invention

what I claim as new and desire to secure by Letters Patent is:—

1. In a device of the kind described, the combination with a casing, provided with a slot in its top, of a rectangular hollow frame provided with a semi-circular portion adapted to be secured over the slot of the casing, a casing provided with a downwardly projecting hood arranged over said frame provided with openings, in its ends, a spring actuated roller mounted in said opening, and a screen carried by the roller, for the purpose described. 30
2. In a device of the kind described, the combination with a casing provided with a slot in its top, of a frame mounted on said casing over said slot, a casing provided with a downwardly projecting hood fitting over said frame, a roller mounted in said casing carrying a screen operating means connected to the screens, for the purpose described. 35
3. In a device of the kind described, the combination with a cylindrical casing provided with a slot adjacent its front end, of a rectangular hollow frame provided with semi-circular portions adapted to be secured 40

over the slot of the casing provided with a downwardly projecting hood adapted to fit over said frame, a screen mounted in the casing provided with the hood and a cord connected to the screen adapted to draw the screen to the bottom of the casing, for the purpose described. 45

4. In a device of the kind described, the combination with a cylindrical casing provided with adjustable supporting members, of a casing arranged over a slot formed in one end of the cylindrical casing, carrying a spring actuated roller, a screen mounted on said roller provided with a curved lower end, a glass door secured on the front of the casing, a flexible tube arranged in the bottom of the casing extending out an opening in the end, a pulley secured to the casing adjacent the end of the tube, and a cord secured to the screen passing out through the tube carrying a ring at its end, for the purpose described. 50

AMERICUS MIESSE.
